(57) CLAIM

The ornamental design for a lipstick case, as shown and described.

DESCRIPTION

FIG. 1 is a perspective view of a lipstick case showing my design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof;

FIG. 7 is a rear elevational view thereof;

FIG. 8 is an exploded perspective view thereof;

FIG. 9 is a perspective view of an alternate embodiment of the lipstick case showing my design;

FIG. 10 is a top plan view thereof;

FIG. 11 is a bottom plan view thereof;

FIG. 12 is a right side elevational view thereof;

FIG. 13 is a left side elevational view thereof;

FIG. 14 is a front elevational view thereof;

FIG. 15 is a rear elevational view thereof; and,

FIG. 16 is an exploded perspective view thereof.

The broken lines depicting the remainder of the lipstick case show features that form no part of the claimed design.
